CLAIM

The ornamental design for an insulator for an electrical cutout, as shown and described.

DESCRIPTION

FIG. 1 is a perspective view of an insulator for an electrical cutout showing our new design;
 FIG. 2 is a front elevational view thereof;
 FIG. 3 is a side elevational view thereof;
 FIG. 4 is a top plan view thereof;
 FIG. 5 is a bottom plan view thereof;
 FIG. 6 is a rear elevational view thereof;
 FIG. 7 is a side elevational view thereof and opposite the side elevational view illustrated in FIG. 3;
 FIG. 8 is a horizontal sectional view taken along line 8—8 of FIG. 2;
 FIG. 9 is a horizontal sectional view taken along line 9—9 of FIG. 2;
 FIG. 10 is a horizontal sectional view taken along line 10—10 of FIG. 2; and,
 FIG. 11 is a horizontal sectional view taken along line 11—11 of FIG. 2.

FIG. 1.

Fig. 6.

Fig. 7.

FIG. 8.

FIG. 9.

FIG. 10.

FIG. 11.
